(57) **CLAIM**

The ornamental design for bracket, as shown and described.

DESCRIPTION

FIG. 1 is a top perspective view of the extruded bracket showing my new design;

FIG. 2 is a top view of the bracket of FIG. 1 (the bottom view being a mirror image thereof);

FIG. 3 is a front view of the bracket of FIG. 2; and,
FIG. 4 is a right side view of the bracket of FIG. 2.**1 Claim, 1 Drawing Sheet**
